UNITED STATES PATENT OFFICE.

WILLIAM ANSON AND JOHN DEELEY, OF BIRMINGHAM, COUNTY OF WARWICK, ENGLAND.

BREECH-LOADING FIRE-ARM.

SPECIFICATION forming part of Letters Patent No. 297,907, dated April 29, 1884.

Application filed November 7, 1883. (No model.) Patented in England April 11, 1883. No. 1,833.

To all whom it may concern:

Be it known that we, WILLIAM ANSON and JOHN DEELEY, subjects of the Queen of Great Britain, residing at Birmingham, in the county 5 of Warwick, England, gun-makers, have invented certain new and useful Improvements in Breech-Loading Hammerless and other Guns and Rifles, (for which we have obtained a patent in Great Britain, No. 1,833, bearing date 10 April 11, 1883,) of which the following is a specification.

The object of our invention is to effect certain improvements in the well-known hammerless or drop-down gun patented by us, 15 and called "Anson and Deeley's patent," dated May 11, 1875, No. 1,756, in which the cocking of the gun is effected by the dropping of the barrels for charging, by means of two dogs or lifters, the fulcrum of which is concentric with 20 the center of the ordinary joint, the dogs or lifters passing through the joint of the breech-action, and also passing through the back or joint part of the fore end.

The invention consists in the novel construction and combination of devices hereinafter described and claimed; and in order that our said invention may be clearly understood, reference is hereby made to the accompanying drawings, in which similar letters of reference 30 indicate corresponding parts in the several figures.

Figure 1 is an elevation of so much of the breech of a double-barreled drop-down gun as is requisite to explain our improvements. 35 Fig. 2 is a top view of the same. Fig. 3 is a sectional elevation on the line *a a* of Fig. 2. Fig. 4 is a sectional elevation on the line *b b* of Fig. 2, representing the gun as it appears after discharge. Fig. 5 is a view of the under 40 side of Figs. 1 and 2. Fig. 6 is a separate plan view of the double lifter. Fig. 7 is a side view of the same, and Fig. 8 a section on the line *c c* of Fig. 6. Fig. 9 is a separate perspective view of the lower bolt, *d*, (shown also in Fig. 45 3,) and Fig. 10 is a plan view of the upper bolt, *e*. Fig. 11 represents the gun cocked by the dropping of the barrels and ready for loading, on the line *b b* of Fig. 2; and Fig. 12 is a

detail side view showing a modified arrangement of spring for throwing the upper and lower 50 bolts forward by acting on the hand-lever.

The lifters *f f* are formed of one piece of metal, the two lifters being united by the cross-piece *g*, which forms a bridge across the slot in the breech-action near the joint-pin *h*. The 55 bridge also spans over the lump of the barrels. When the barrels are "dropped," the portion marked *i* of the fore-end lever presses the lifters *f f* backward by its contact with *g*, and consequently their inner ends rise in a radial line 60 with the center *h*, as shown in Fig. 11. The inner ends of the lifters being in contact with the tail ends of the hammers *k*, the latter are lifted to the position of "cock." As also shown in Fig. 11, the lump does not form any part of the 65 cocking arrangement, but merely turns on the joint-pin, as in ordinary guns.

It is obvious that the lifter *f f*, by a slight modification, can be adapted to single-barrel drop-down guns. 70

The lower bolt, *d*, has an opening, *d'*, through which one of the lugs *l* passes and enters the lugs at *l' l'*, and the upper bolt, *e*, also enters the recess cut out at *e'*, thereby holding the barrels down during discharge. The upper 75 bolt, *e*, and lower bolt, *d*, are simultaneously withdrawn, in order to let the barrels drop, by pushing aside the hand-lever *m*. This hand-lever is pivoted at *m'*, Fig. 2, to the upper bolt, *e*; but the hand-lever is also pivoted at 80 *m''* to a fixed center. This arrangement causes the pivot at *m'* to recede when the hand-lever is pushed aside, and this receding movement causes the upper and lower bolts to release the barrels. The connection between the actuating 85 mechanism of the upper and lower bolts is effected by means of the angle-piece *n*, the mode of connection being behind instead of in front of the breech-pin, as is clearly shown in the drawings, Figs. 3 and 4. The bolts are 90 pressed forward, by means of the spring *o*, between the provision *p* and thrust-block *q*; but instead of this spring we sometimes substitute the side spring, *r*, (shown in Fig. 12,) which operates upon the hand-lever *m*, as shown. 95

By the foregoing arrangements there is an

increased simplicity in the working parts. The strength is also increased, and the wood is not cut away in front of the breech-pin.

Having thus particularly described and ascertained the nature of our said invention, and in what manner the same is to be performed, we claim—

1. In a breech-loading fire-arm, the combination of the drop-barrel having the lug l , provided with front and rear recesses, $l' l''$, and the recess e' at the upper portion of the breech end, the lower bolt, d , having the slot d' and angle-piece n , the upper bolt, e , the lever m , swinging on a fixed pivot, m^2 , at the upper side of the breech, a pivot, m' , connecting the upper bolt with the lever at one side of its pivot m^2 , and a connection between the rear end of the upper bolt and the rear end of the angle-piece n on the lower bolt, substantially as described.
2. In a breech-loading fire-arm, the combination of the drop-barrel having on its under side the projection i , the separated lifters $f f$, rigidly connected by the transverse bridge-piece or bar g , a single pivot-pin, on which both the lifters are journaled above their connecting-bar, said pivot-pin being concentric with the joint of the barrel and breech, and the pivoted hammers k , the said projection on the barrel, when the latter is dropped, acting on the bridge-piece or bar to simultaneously swing the connected lifters and cock the hammers, substantially as described.
